United States Patent

Des. 237,863
Patented Dec. 2, 1975

237,863

COMBINED BOTTLE AND CAP THEREFOR

Bernd Peters, Jesteburg, and Hermann G. Quack, Hamburg, Germany, assignors to Colgate-Palmolive Company, New York, N.Y.

Filed Mar. 8, 1973, Ser. No. 339,031

Claims priority, application Great Britain Sept. 14, 1972

Term of patent 14 years

Int. Cl. D9—01

U.S. Cl. D9—168

FIG. 1 is an elevational view of a combined bottle and cap therefor showing our new design, the opposite side being substantially the same in appearance;

FIG. 2 is an elevational view looking from the right of FIG. 1, the opposite side being substantially the same in appearance; and

FIG. 3 is a top plan view thereof.

We claim:

The ornamental design for a combined bottle and cap therefor, as shown and described.
